(57) **CLAIM**

The ornamental design for a “kitchen scale,” as shown and described.

DESCRIPTION

FIG. 1 is a top perspective view of a kitchen scale, showing our new design;

FIG. 2 is a top plan view of the kitchen scale shown in FIG. 1; FIG. 3 is a bottom plan view of the kitchen scale shown in FIG. 1;

FIG. 4 is a front view of the kitchen scale shown in FIG. 1; FIG. 5 is a rear view of the kitchen scale shown in FIG. 1; FIG. 6 is a right side view of the kitchen scale shown in FIG. 1; and,

FIG. 7 is a left side view of the kitchen scale shown in FIG. 1. The subject matter shown in dashed lines is for illustrative purposes and forms no part of the claimed design.

1 Claim, 5 Drawing Sheets
